UNITED STATES PATENT OFFICE

FREDERICK H. JOHNSON, OF DETROIT, MICHIGAN

ADVERTISING SIGN

Application filed October 16, 1929. Serial No. 400,127.

This invention relates to an advertising sign and is illustrated as embodied in a sign adapted for use on an automobile.

The type of sign to which the invention primarily relates is that in which a light passing through a stencil or the like is reflected by means of a reflecting surface in the direction in which the sign is to be viewed.

An object of the invention is to provide an improved sign in which daylight, preferably direct from the sky, can be reflected through the stencil or the sign can be illuminated artificially in any manner when the daylight is insufficient for that purpose.

15 Heretofore, advertising signs have been arranged on the top of an automobile body and it has been customary to provide a sun visor on the front of the automobile body over the windshield. These two units are unsightly and when made as separate units increase the cost of manufacture as well as add to the cost of the assembly. It is therefore another object of the invention to combine the two into a single unit, the upper surface of the 25 sun visor serving as a reflector for the light passing through the stencil.

Other objects and advantages of the invention will more fully appear from the following description taken in connection with the 30 accompanying drawings in which:

Fig. 1 is a front elevation of a portion of a vehicle body showing an adaptation of my improved device.

Fig. 2 is a view corresponding to Fig. 1 showing a modified form of my device.

Fig. 3 is an enlarged fragmentary view showing in side elevation the form of my device illustrated in Fig. 1.

Fig. 4 is a sectional view on line 4—4 of 40 Fig. 3.

Fig. 5 is a sectional view on line 5—5 of Fig. 1.

Fig. 6 is a sectional view on line 6—6 of Fig. 3.

45 Fig. 7 is a fragmentary view taken on line 7—7 of Fig. 3, parts being broken away and in section.

Fig. 8 is a sectional view on line 8—8 of Fig. 2.

50 Referring to the drawings wherein I have

illustrated one form of my device, the reference numeral 10 designates the upper portion of a vehicle body having a top 12 and a front windshield frame 14. A windshield 16 is arranged in the frame 14.

Referring particularly to Figs. 3 and 4, I have provided an upper rectangular frame structure 18, extending generally in a horizontal plane, adapted to receive a stencil 20. The term "stencil" is hereinafter to be understood to mean a sign plate having advertising thereon through which the light may pass. It may consist of a glass panel with the sign painted thereon or it may consist of a shield having openings through which the light may pass to be used with or without a glass panel. In the form of my invention shown, a glass panel 22 is mounted in the frame 18, and the frame 18 is welded at its opposite ends or otherwise secured to end angle frames 24. The end angle frames 24 are secured to end walls 26, such as by welding indicated at 28. The inner face of the bracket 24 is provided with a plurality of projections 30 upon which the frame 18 rests. The rear side of the frame 18 is secured to a rear wall stamping 32 which has an inwardly extending flange 34. The end walls 26 have a portion extending above the plane of the stencil 20 which is concaved as at 36 and a portion extending vertically below the stencil 20. On the inner faces of the downwardly extending portion I have secured, such as by welding, angle members 38 angularly disposed with relation to the stencil 20. A

plate 40 has its opposite ends secured to the angle members 38 and its side edge secured to the flange 34 of the back stamping 32. The plate 40 extends generally in a plane at about 45 degrees to the plane of the stencil 20, the rear side edges of the stencil 20 and plate 40 being adjacent. An attaching flange 42 has been formed on the end wall 26 which is secured to the front pillar of a vehicle body or to the windshield frame 14. If desired to more rigidly secure the assembly to the vehicle body, fastening devices such as screws 44 may be inserted through the stampings 32 engaging the forward face of a body

frame member.

The stencil 20, which in the form illustrated, comprises a glass 22 having a sign, indicated at 46, painted on the under surface of the glass 22. The plate 40 may consist of a mirror, but I prefer to use a metallic plate having a coating of chromium on its upper surface as indicated at 46.

By the arrangement of the stencil, extending generally in a horizontal plane, and the reflecting plate 40 extending below the stencil and at an angle to the stencil, light shining through the stencil is reflected from the plate 40 in substantially a horizontal line.

It is often desirable to display the sign at night and such requires the use of artificial lighting means. As a means for accomplishing this end, I have provided an electric light bulb 48 extending thru a wall 49 of the bracket 24 at the ends of stencil 20. The electric bulb 48 is positioned in a suitable socket 50 having a reflector 52 secured to the socket 50. The reflector 52 conforms generally to the concave surface of the upper portion 36 of the end wall 26. The upper edge of the concave portion 36 is provided with a bezel 52 which secures a lens 54 in a vertical position, the lower edge of the lens being received in a channel of the bracket 24. It is important to properly position the bulb 48 vertically relative to the stencil 20. I have therefore secured a bracket 56 to the end wall 26 and have placed a screw 58 in an inwardly extending flange of the bracket 56. The screw 58 is in screw thread engagement with a portion of the reflector 52 so that when the screw 58 is turned, the reflector, bulb and socket may be adjusted vertically. A lock nut 60 has been provided on the screw 58 to hold the screw in adjusted position.

Referring to Fig. 7, wherein I have illustrated a means for inserting the glass 22 in the frame 18, the forward portion of the frame 18 is detachable from the rear end portions 22. A block member 62 is secured to the forward channel portion 18. A screw 64 passing through the block member 62 is screw threaded into a member 66 carried by the end wall 26. When it is desired to remove the glass 22, the screw 64 is removed and the forward channel 18 is removed. The glass may then be slid forward out of the rear and end sections of the channel 18. The bezel 52 is held in position around the edges of the concave portion 36 and the lens 54 by screws 68, screw threaded into the member 66.

It will be understood that the stencil 20, panel 40, end walls 26, and lights 48 are assembled as a single unit and that this unit is detachably received on the front surface of a vehicle body such as the frame work for the top or the frame work for the windshield. The plate 40 serves as a sun visor and at the same time serves as a reflector for the light 48 through the stencil.

Referring to Figs. 2 and 8 wherein I have illustrated a modified form of my invention, the stencil 70 is secured to the under surface of a plate 72 having a rectangular opening 74 over the stencil. The stencil 70 and plate 72 extend generally in a plane with the plane of the vehicle top. The stencil extends forwardly of the vehicle body and the plate 72 is secured on the upper portion of the top frame 76, overlapping the edge of the top covering 78. The end walls of this form of my device, consist of flanges 80 bent downwardly from the top plate 72. The flanges 80 are provided with inwardly turned flanges 82 which receive a sun visor 84. A rear face of the sun visor is secured to the forward face of the frame 76 by screws 86 extending through an upwardly turned flange 88. The forward edge of the sun visor 84 is provided with a return bend 90 which receives a reflecting surface 92, such as a mirror or a chromium plated panel. A bracket 94 is arranged between the forward edge of the sun visor 84 and the front face of the frame 76.

As a means for reflecting artificial light through the stencil, I have arranged a plurality of lamps 96 on the upper surface of the plate 72. Each lamp is provided with two lenses, one a bull's-eye 98 which may be colored, and the other a transparent lens 99 which reflects light through the stencil 70, there being electric light bulbs and suitable reflectors in the lamps 96.

Although two specific embodiments of this invention have herein been shown and described, it will be understood that various changes, including the size, shape and arrangement of parts, may be made without departing from the spirit of my invention and it is not my intention to limit its scope other than by the terms of the appended claims.

1. A device of the class described comprising a visor disposed at the upper portion of an automobile windshield extending at an angle thereto, and a stencil above said visor extending at an angle to the panel and to the windshield, the upper surface of said visor having a reflecting surface.

2. A device of the class described comprising a sun visor disposed at the upper portion of an automobile windshield extending downwardly and forwardly therefrom, a stencil above said sun visor extending from the upper portion of the windshield and at approximately right angles thereto, the upper surface of said sun visor having a reflecting surface.

3. A device of the class described comprising a sun visor disposed at the upper portion of an automobile windshield extending at an angle thereto of approximately 45 degrees, a stencil disposed at the upper portion of the windshield extending generally at right angles thereto over the sun visor, the upper sur-

face of said sun visor being chromium plated.

4. A device of the class described comprising in combination, an automobile body having a windshield frame, a stencil extending 5 from the upper surface of the windshield frame and in the plane of the body top, and a sun visor having an upper reflecting surface below said stencil on said windshield frame.

10 5. A device of the class described comprising a sun visor having its upper surface provided with a reflecting surface, and means associated with said sun visor for projecting an image on said reflecting surface.

15 6. A device of the class described comprising a sun visor disposed on an automobile body extending downwardly and forwardly therefrom, the upper surface of said sun visor having a reflecting surface, and means associated with said sun visor for projecting an 20 image on said reflecting surface.

25 7. A device of the class described comprising in combination an automobile top having a front frame member, a covering for said top secured to said frame member, a transparent panel projecting forwardly from said top having a flange overlapping the forward edge of said covering, a stencil in said transparent panel, and a reflecting panel below 30 said stencil secured to the forward face of said top frame member.

35 8. A device of the class described comprising a horizontally disposed stencil, vertically disposed end walls having portions projecting above and below said stencil, an adjustable artificial light source in the portion of the end walls above said stencil, an angularly disposed reflecting panel between the portions of the end walls below said stencil, and attaching means on said end walls.

FREDERICK H. JOHNSON.
